UNITED STATES PATENT OFFICE.

GEORGE J. LETCHWORTH, OF BUFFALO, AND JOSIAH LETCHWORTH, OF AUBURN, NEW YORK.

HAME.

SPECIFICATION forming part of Letters Patent No. 249,958, dated November 22, 1881.

Application filed June 4, 1881. (No model.)

To all whom it may concern:

Be it known that we, GEORGE J. LETCHWORTH, of the city of Buffalo, in the county of Erie and State of New York, and JOSIAH LETCHWORTH, of Auburn, in the county of Cayuga and State of New York, have invented new and useful Improvements in Hames, of which the following is a specification, reference being had to the accompanying drawings.

10 The object of this invention is to produce a light, strong, and durable hame having a neat and finished appearance.

Our invention consists, to that end, of a hame composed of a metallic body having a groove or depression and a wooden or other suitable filling secured in the groove or depression of the metallic body, as will be hereinafter fully set forth.

15 In the accompanying drawings, Figure 1 is a front elevation of our improved hame. Fig. 2 is a front elevation of the filling. Fig. 3 is a front elevation of the metallic body of the hame. Fig. 4 is a horizontal section on an enlarged scale in line *xx*, Fig. 1. Fig. 5 is a similar cross-section, showing a modified construction of our improved hame.

Like letters of reference refer to like parts in the several figures.

20 A represents the metallic body of the hame, which is formed by a trough or channel-shaped plate composed, as shown in Figs. 1, 3, and 4, of a back plate, *a*, adapted to fit against the collar, and two forwardly-projecting marginal flanges, *b b*.

25 C represents a filling, of wood or other suitable material, made of the proper shape to fit in the depression or groove in the metallic body A, between the flanges *b b* thereof. The rear side of the filling C fits against the back plate, *a*, of the metallic body A, and its front or face side is made of any desired form. The filling C is secured to the metallic body A by rivets *d*, or other suitable fastenings. The metallic body A is preferably constructed of malleable cast-iron, and provided with the usual loops, hame-eye, and terrets, which may be cast in one piece with the body, or otherwise.

30 In the modified construction represented in Fig. 5 the metallic body A constitutes the front

or face portion and the side portions of the hame, and the filling C is secured in the depression or groove which is formed on the rear side of the body. The rear side of the filling bears against the collar and its convex front side against the similarly-curved front side of the metallic body.

35 In manufacturing our improved hame the cast metallic bodies are japanned, tinned, or otherwise finished, and the wooden fillings, which are cut by suitable machinery, are painted separately, and after these parts are so finished the body A and filling C, constituting one hame, are secured together. In this manner the operation of finishing the metallic part is prevented from defacing the wooden part of the hame, and vice versa, and a neat-looking hame is thereby very cheaply produced. The filling serves not only to strengthen the hame, but prevents the accumulation of dirt in the groove of the hame, and where it is applied to the rear side of the metallic body, as shown in Fig. 5, it prevents the edges of the grooved hame from being pressed into the collar and forming creases therein.

40 We claim as our invention—

1. A hame composed of a cast metallic body, A, provided with a groove or depression, and a filling, C, of wood or other suitable material, secured in said groove or depression, forming one of the outer-side surfaces, substantially as set forth.

2. A hame composed of a metallic body, A, formed by a back plate, *a*, cast with forwardly-projecting flanges *b b*, and a filling, C, secured in the depression of the body between the flanges *b b*, forming an outer surface on one side, substantially as set forth.

G. J. LETCHWORTH.
JOSIAH LETCHWORTH.
